PIN PUNCH GUIDE

Joseph E. Morvey, Flushing, N. Y.

Application March 17, 1948, Serial No. 15,289

2 Claims. (Cl. 81—1)

1

This invention relates to a guide for use with pins, punches and the like used to fasten a plurality of objects together or to remove already inserted fastening pins from their embedded position in an object. The product of the new invention is extremely economical and of high practical value for a multitude of operations.

The new guide has but a minimum of parts, yet will be found useful in connection with a multitude of pins of various sizes and in connection with pinning and punching operations involving objects having various sizes and forms. The new device cooperates with guiding fingers yet provides complete safety for such fingers heretofore frequently subjected to bruises when used to guide pins or punches. Portions of the product of the present invention serve to, respectively, securely hold the device on a surface and to ward off any blow which otherwise may strike the fingers of the person conducting the operation.

The device of the present invention comprises two angular walls having cooperating rounded marginal cutouts to permit positioning of a finger, squared top portions to accept hammer blows, and bottom portions, often squared, which conform to the surface of the material where the pins are to be embedded.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is an elevational view of the device of the present invention.

Fig. 2 is a frontal elevational view showing the device of the preceding figure with a pin in position.

Fig. 3 shows the device of the preceding views during actual operation in perspective.

Fig. 4 is a top view showing the device in operation.

Fig. 5 illustrates an elevational view of another embodiment of the invention.

Fig. 6 is a like view showing the product of Fig. 5 during actual operation.

Fig. 7 is a frontal perspective view of yet another embodiment of the instant invention.

Fig. 8 shows the device of the preceding figure with a pin in position.

In accordance with the invention the guide is formed of two walls 10 and 11 in angular posi-

tion to each other and meeting at edge 12. The angle between the two walls 10 and 11 may be 90° and will often approximate 90°. The two walls 10 and 11 conveniently have centrally located rounded cut out portions 13 and 14 located at the same or approximately the same height. They are further cut off to provide a square top portion 15 and a squared or rounded bottom portion 16 to conform to the surface of an object 10 to which the guide is applied.

In accordance with the preferred mode of operation of the instant invention, a pin 17 is aligned against the two angular walls 10 and 11 and held in position by a thumb 18 holding the pin and pressing into cut out portions 13 and 14 and cooperating with index finger 19 to rigidly hold the device in position. The surface 16 is thus pressed against e. g. a rounded object 20 at first movably mounted on a V-block 21 and the pin 17 is aligned directly above hole 22 in said rounded object 20. A hammer 23 is used to drive pin 17 into hole 22 with the surface 15 serving to protect the otherwise exposed thumb 18 against any careless hammer blows.

In accordance with the modification shown in Figs. 5-6, one of the angular surfaces 19 ends at its upper end in a rounded index finger guard 24 snugly fitting an index finger 19. The operation of this embodiment of the invention best shown in Fig. 6 where two flat plates 25 and 26 are attached to each other by means of a multitude of pins 27. Guard 24 is simply placed around index finger 19 permitting better grasping and readier handling of the guide and insuring added safety to the index finger. The thumb 18 fits into depressions 13 and 14 and other phases of the use of this embodiment are analogous to the ones of the preceding embodiment.

In accordance with yet another embodiment of the invention best illustrated in Figs. 7-8, the two walls 10 and 11 are perforated at edge portion 12 conveniently by means of centrally located perforation 28 so as to provide added safety and positive guidance in a convenient recess for index finger 19. The device has all the other features of the embodiment of Figs. 1-6 and is accordingly used.

It will thus be seen that novel guide for many types of pins and punches applicable by obvious modification to tapering pins has been devised. The new structure combines optimum safety with great simplicity and usefulness with a large variety of pins and attachable structures greatly varying in size and form.

While I have illustrated and described the

preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A guide for guiding of pins comprising two walls arranged angularly with relation to each other with adjacent edges secured together and having cooperating centrally located rounded depressions for a thumb and forming cooperating top surfaces warding off misdirected hammer blows and also cooperating bottom members conforming to the surface of an object to be pinned, said two walls being centrally perforated along their meeting edge permitting a recess for a finger.

2. A guide for guiding of pins comprising two

walls arranged angularly with relation to each other with adjacent edges secured together and having cooperating centrally located rounded depressions for a thumb, said angular walls having a rounded opening at the junction of their adjacent edges forming a recess for an index finger.

JOSEPH E. MORVEY.
